WIND INSTRUMENT

Filed Oct. 24, 1921

UNITED STATES PATENT OFFICE.

ALSON F. FAIRCHILD, OF ELKHORN, WISCONSIN.

WIND INSTRUMENT.

Application filed October 24, 1921. Serial No. 510,182.

To all whom it may concern:

Be it known that I, ALSON F. FAIRCHILD, a citizen of the United States, residing at Elkhorn, in the county of Walworth and State of Wisconsin, have invented certain new and useful Improvements in Wind Instruments; and I do hereby declare the following to be a full, clear, and exact description of the invention such as will enable others skilled in the art to which it appertains to make and use the same.

This invention relates to musical wind instruments, of the cornet and horn type, and the object of the invention is to simplify and improve the construction of the air-valves and correlated parts of such instruments.

As usually constructed, cornets and other wind instruments of this type are provided with three or more cylinders fitted with pistons manipulated by the fingers, and each pierced with three air-passages through which the air is transmitted to different looped air-pipes of the instrument as the pistons are moved in or out. These air-passages are disposed in peculiar ways, diagonal to the pistons, no two of which are alike. To accurately form the ports or air-passages is a matter of nicety and difficulty, and adds very considerably to the cost in the manufacture of the instrument. In my improved construction the pistons are all alike, and each has but two, easily formed conduits.

The invention is fully disclosed in the description and claims following, reference being had to the accompanying drawing, in which:

Fig. 1 is a side elevation of a wind instrument embodying my invention, with the mouth-piece and bell end omitted. Fig. 2 is a plan view of the same, as seen from below. Fig. 3 is an enlarged elevation of one of the pistons, the cylinder being in section. Fig. 4 is a vertical section of the middle piston, its cylinder and connected pipes. Fig. 5 is a similar section, showing a modification in the construction of the piston. Fig. 6 shows in section another modification, in which the slide-valve is a flat plate, with attached tubular loops.

In the drawing, the numerals 1, 2 and 3 denote the cylinders of the most common type of horn, to which the mouth-piece, bell-pipe and the several looped pipes connect. The piston and cylinder are fitted telescopically, as shown. They may be, respectively,

of identical form and structure, and are pierced at 4, 5, 6 and 7 with aligned and equally spaced holes. Cylinders 1 and 2 connect at 5 by a short, semi-circular loop 60 of pipe 8. Cylinders 2 and 3 are connected in the same manner at 6. A little longer loop 10 connects the extreme holes of cylinder 2. A longer loop 11 connects the same holes of No. 3. The mouth-piece connects 65 with No. 3 at 5, and the bell-pipe with No. 1 at 6.

Various embodiments of my invention are shown in Figs. 3, 4, 5 and 6. The upper end of the piston in Figs. 3, 4 and 5 is substantially the same as in the piston in general use, having a stem 14 provided with a button or key 15, a return-spring 16 set in the slotted upper end of the tube or piston barrel, and a bridge-plate 17 projecting through 70 the slots, and serving as a seat for the spring. Suitable provision is made to prevent the bridge from turning, but this is a well-known device, and need not be described.

The body of the piston is provided with a 80 pair of semicircular conduits 13^a and 13^b. These conduits are formed of curved pieces of tubing, whose openings coincide with the holes in the piston, and are suitably secured inside the same as by soldering. In the 85 type of piston shown in Fig. 6 a simple, flat plate 13^y is used, the construction and attachment of the conduits being similar, but very simple mechanically. The abutting face of the receiving cylinder in this case is 90 a flat-guide-plate 2^a in which the piston-plate slides, the cylinder being suitably depressed on one side, as shown. The various looped air-pipes connect with this flat guide-plate in the same manner as to the cylindrical forms shown in other figures.

The pistons are shown in initial position in Figs. 1, 5 and 6, in which case open tones are produced, the air taking the shortest course, through the mouth-pipe loops 8 and 9 and the bell-pipe. Fig. 4 shows the piston of No. 2 depressed in which case the air must pass through loop 10. Similarly the depression of the other pistons will cause the air to pass through other loops 11 or 12 105 as the case may be. When the piston is in the initial position the conduit 13^a is not in use, as will be evident from Figs. 5 and 6.

The instrument is played in the same manner as horns in general use, the open tones being the same, and those produced by fingering corresponding to those pro-

duced by the same fingering of the ordinary instrument. The tones are clear and pure, and are produced with less effort than is required with other instruments. It is to be noted that the action of the keys is freer and more responsive than in other horns due in part to the fact that the pistons, may be smaller, with a shorter stroke, yet with equal air capacity.

10 In the matter of manufacture, the construction has many advantages. Instead of the three parts in other pistons, the head, spring-barrel and piston top, my piston and spring barrel in the cylindrical type, are 15 made from one piece of tubing, and that smaller than others, as above mentioned.

Whether of the cylindrical or flat type, the respective parts are duplicates, any piston fitting any cylinder of its type. This 20 of course greatly simplifies manufacture one boring of holes, for example, serving for all. As there is no diagonal disposition of air-ports, there need be no indentation of their walls anywhere, as is the common practice 25 in the construction of the ordinary instrument. So in the fitting, assembling and adjustment of parts, the operations are very simple, since the ports are all in a straight line, and the pistons need only to be guided 30 in such a line, and stopped at the proper terminals.

The invention is adapted for all band and orchestra horns large or small, the size in any case corresponding to the size of the 35 instrument.

Having thus described my invention, I claim:

1. In a wind-instrument, a finger-operated piston, having plural curved conduits with 40 aligned and equally-spaced inlets and outlets wholly in one side thereof.

2. In a wind-instrument, a finger-operated piston, having two conduits equally spaced with aligned inlets and outlets wholly in one 45 side thereof, and an enclosing cylinder having four aligned holes registering with both ports in one position, and two holes registering with one port in the shifted position of the piston.

3. In a wind-instrument, a finger-operated 50 piston, having curved conduits with aligned equally spaced inlets and outlets wholly in one side thereof, an enclosing cylinder therefor, having an equal number of holes registering with said openings, and looped 55 pipes of various lengths connecting with said holes.

4. In a wind instrument having a plurality of pistons in duplicate, each provided with a pair of curved conduits with aligned 60 openings equally spaced inlets and outlets wholly in one side thereof, a plurality of duplicate cylinders with aligned holes in register with an equal number of said piston openings, a mouth-piece connecting with 65 a hole of one cylinder, a bell-pipe connecting with the opposite corresponding hole of the cylinder farthest therefrom, and looped pipes of various lengths connecting corresponding holes in each cylinder, and opposite 70 holes in pairs of cylinders.

5. Air-controlling mechanism for wind-instruments, comprising triple cylinders, each pierced at one side only with four aligned air-holes, looped pipes of various 75 lengths connecting the terminal holes of each cylinder, short loops connecting two pairs of holes in different cylinders in staggered order, a mouth-piece connecting with one of the remaining holes, and a bell-pipe 80 connecting with the other, and pistons provided with curved conduits registering with all of the cylinder holes when opened to normal position, and registering by a single port with another pair of holes, when depressed.

6. In a wind-instrument, a slide-valve, having in one side only four aligned equally spaced openings connected in pairs by curved air-passages, and a guide for said 90 valve, with like aligned and spaced openings, and air-pipes leading therefrom.

In testimony whereof I affix my signature in presence of two witnesses.

ALSON F. FAIRCHILD.
